UNITED STATES PATENT OFFICE

ARTHUR SCHORNO, OF BADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND

SAFETY BRAKE APPARATUS

Application filed February 28, 1927, Serial No. 171,392, and in Germany March 12, 1926.

This invention relates to winding apparatus, such as of the type employed in mine hoists. It has to do particularly with forms of such apparatus wherein provision is made for the uncoupling of the winding drum from its operating shaft, for such purposes as to permit adjustment of the length of the winding rope, or adjustment of the drum with respect to the shaft or with respect to an associated drum adapted to be operated by the shaft and conjointly with the adjustable drum.

The general object of the invention is the provision of apparatus of this type having automatically operating safety provisions effective to limit or prevent unintentional rotation of the drum while it is uncoupled from its normal operating means.

Another object is the provision of apparatus of this type in which the safety devices are disconnected or cut out when the apparatus is in normal operating condition, but are cut in automatically incident to the uncoupling or the unclutching of the drum from its normal operating means.

A further object is a provision of apparatus of this type which is positive and certain in operation and simple in construction.

Other and further objects will be pointed out or indicated hereinafter or will appear to one skilled in the art upon an understanding of the invention or its employment or practice.

In the drawings forming part of this specification, I show in diagrammatic or schematic fashion, various arrangements of apparatus in which the invention may be embodied, but it is to be understood that these are here presented for purpose of illustration only, and are not to be accorded any interpretation calculated to limit the claims short of the true and most comprehensive scope of the invention in the art.

In the drawings Fig. 1 is a diagrammatic illustration in the nature of a cross section of winding apparatus including two winding drums arranged for operation by a single shaft, together with certain portions of the braking and automatic safety equipment.

Fig. 2 is a similar diagrammatic illustration of like apparatus differing in certain respects from that shown in Fig. 1.

Figs. 3 and 4 are similar diagrammatic illustrations of other arrangements of the automatic control devices, the drums being shown in elevation.

Fig. 5 is a top view of an adjusting device by which one of the safety switches may be regulated.

In various kinds of winding apparatus as, for example, in mine hoisting engines of the double drum type, in which the hoisting rope is wound onto one drum while being unwound from a conjointly operated drum, it may be necessary from time to time to uncouple either one or both of the drums for such purposes as adjusting the length of the rope or for hoisting from different levels. It is important that very positive control of the uncoupled drum be maintained, as the drums usually are heavily loaded, and any failure of the holding devices or brakes may result in the rotation of the drum by its load with resulting serious consequences. When the drum is under normal operating control, however, it must be free for rotation by the normal operating means in either direction as desired, without interference from emergency safety devices.

The present invention provides a form of apparatus which affords an automatically operating safety control for the drum during the time it is uncoupled from its normal operating means. This automatic safety control is cut out during the time that the drum is under control of its normal operating means, so that the safety control does not in any fashion interfere with or complicate the normal operation of the machine, but is automatically put into condition for operation incident to the disconnection of the drum from its normal operating means.

The nature of the invention will be ascertained in more detail from the exemplifications shown in the drawings. Referring to that illustrated in Fig. 1, let it be understood that the numeral 10 designates the driving means or drum operating shaft which is driven by a suitable prime-mover, and which

carries the two winding drums or operating members 11 and 12. The drum 12 is provided with a clutch mechanism by which it may be operatively secured to or released from the shaft 10. A plate 40, which is freely rotatable about the shaft 10, is provided with pins 41 arranged to extend through apertures in the clutch plate 14 and through apertures in one of the internal bracing plates of the drum. 5

10 A lever 43 pivoted at 44 contacts with a collar on the end of a sleeve 42 and with an operating mechanism 16 for holding brake 15. The pins 41 are normally maintained in engagement in the clutch plate and drum brace apertures by a spring 45 when it is desired to permit the drum to rotate with the shaft 10. The clutch is disengaged by movement of mechanism 16 to operate brake 15, which movement withdraws pins 41 from the drum brace apertures against the action of spring 45, which, when brake 15 is released, causes 15 re-engagement of the clutch.

15 The numeral 15 illustrates a holding element or brake which is utilized for holding the drum 12 stationary when it is uncoupled from the shaft, said brake being operated by appropriate mechanism 16.

20 The numeral 17 designates a safety element or brake which may be brought into operation to hold the drum 12 against rotation upon the concurrence of certain preconceived conditions. Automatic control mechanism is provided for rendering the brake 17 effective upon rotation of the drum 12 while it is uncoupled from the shaft. This includes an operating means for brake 17, such as the spring 18, against the pressure of which the brake may be retracted by operation of the releasing lever 19, and held retracted by a 25 controlling tripping device 20 operable by an electro-magnet 21 which holds the tripping device in effective position, and a spring 22 by which the tripping device may be actuated, when the electro-magnet is deenergized, 30 to trip the brake. The electro-magnet is energized from a source of current 24 in the control circuit 25. It will be understood that preliminary to the operation of the clutch 14 for uncoupling the drum from the shaft, the holding brake 15 is operated to secure the drum. 35 Bevel gear 31 is fixedly secured to drum 12 for rotation therewith. A switch device 26 is operated by the brake 15, said switch closing the control circuit 25 across the terminals 27 when the brake 15 is off, but opening the circuit at those terminals when the brake is applied. An emergency switch device 28 is provided for closing the control circuit 25 across the terminals 29, and said switch is 40 coupled with the drum 12 by means of shaft 30 and gearing 31 and 31' so that rotation of the drum in either direction will move the switch 28 from its mid-position and open the circuit across the terminals 29. The switch 28 may be made adjustable to fixed positions 45

relative to the shaft 30, however, being equipped with a setting device 32 including a ratchet wheel 46 secured to shaft 30 and a pawl 47 adjustable with respect to the ratchet 46, as shown in Fig. 5, whereby the switch may be secured in fixed relationship to the shaft. 70

75 In the operation of the apparatus, when it becomes desirable to uncouple the drum 12 from the shaft, the emergency switch 28 is first adjusted to a position wherein it closes circuit 25 across the terminals 29. The holding brake 15, is then set to perform its function as the normal means for holding the drum stationary. Incidental to setting of the holding brake 15, the switch 26 is opened, but this does not open the control circuit 25 to release the safety brake 17, as the circuit is bridged by the emergency switch 28 so that the tripping magnet 21 remains energized. However, in the event the brake 15 fails to hold the drum, and the latter starts to rotate in either direction, the emergency switch 28 will be moved to open the control circuit, whereupon the tripping device 20 will be operated automatically to set the brake 17 and secure the drum. 80

85 The arrangement illustrated in Fig. 2, the switch, which is operated incident to the uncoupling of the drum, is designated by reference numeral 26' and is operated automatically from the clutch 14'. In this figure the tripping mechanism is not shown, but it may be similar to that illustrated in Fig. 1, being controlled in the circuit 25. The emergency switch 28 is arranged and operated as illustrated in Fig. 1 to control the circuit 25 at the terminals 29. 90

95 In the arrangement illustrated in Fig. 3, the emergency switch 28 is arranged and operated in like fashion, but the normal closing switch 26'' is operated in conjunction with the mechanism for uncoupling a depth indicator 34, an operation which is performed prior to the uncoupling of the drum 12 from the shaft. In this arrangement, the depth indicator 34 is operated by gears 35-36 driven from the shaft 30. The gear 36 is adjustable longitudinally on shaft 30 by a screw device 37, whereby it may be moved into and out of mesh with gear 35. When moved out of mesh, the switch lever 38 is engaged by a stop 39 and moved to open the switch 26'', this operation taking place, of course, after the holding brake 15 has 100 been applied and the emergency switch 28 set to close the control circuit across the terminals 29. 110

115 In the arrangement illustrated in Fig. 4, the emergency switch 28' is operated by a centrifugal device 40 driven from shaft 30 by transmission means 41. The centrifugal device is arranged to operate to open the switch 28' upon any slight rotational movement of the uncoupled drum, and cause the 120

tripping of the safety brake. It will be understood that in the arrangements illustrated in Figs. 3 and 4 the tripping mechanism is operated in the control circuit 25, as in the manner illustrated in Fig. 1.

5 What I claim is:

1. In apparatus of the character described, an operating member, driving means therefor, a plurality of elements for holding said member against operating movement and disposed for movement independently of each other into and out of holding position, means for controlling movement of one of said elements into holding position, a plurality of devices each operable to control said controlling means, means for actuating one of said controlling devices, and means responsive to operating movement of said member and being operable upon such movement to effect 20 actuation of the other of said controlling devices.

2. In apparatus of the character described, a rotatable operating member, a plurality of means for retarding movement of 25 said operating member, means for controlling movement of one of said retarding means in dependence on movement of another of said retarding means, and means for operating said controlling means upon failure of 30 operation of one of said retarding means.

3. In a device of the character described, a plurality of rotatable operating members, a plurality of retaining means for one of said operating members, electrical means for controlling operation of one of said retaining means, and means for actuating said electrical control means upon failure of one of 35 said retaining means to prevent rotation of said operating member, said control actuating means and one of said retaining means co-operating to control operation of said electrically-controlled retaining means.

4. In a structure of the character hereinbefore described, rotatable drums, means for rotating said drums, means for disconnecting one of said drums from said driving means, brakes for retaining said disconnected drum in a predetermined position, an electrically operated trip for controlling the movement 45 of one of said brakes, a source of electric current for operating said trip, and contacts in circuit with said trip operating means and said source of current arranged to be bridged by the action of another of said brakes.

5. In a structure of the character hereinbefore described, rotatable drums, means for rotating said drums, means for disconnecting one of said drums from said driving means, brakes for retaining said disconnected drum in a predetermined position, an electrically operated trip for controlling the movement 55 of one of said brakes, a source of electric current for operating said trip, a plurality of pairs of contacts, the contacts being in circuit with said trip and said source of current, one

pair of said contacts being arranged to be bridged by the action of another of said brakes, and means for bridging another pair of said contacts upon failure of said last-mentioned brake to prevent rotation of said drum. 70

6. In drum controlling means for hoisting devices, a plurality of rotatable drums, means for driving said drums, means for disconnecting one of said drums from said driving means, a plurality of brakes for retaining 75 said drum in predetermined position, electro-magnetically operated means for controlling one of said brakes, means operable by another of said brakes for partially effecting operation of said electro-magnetic control 80 means, and means operable upon movement of said disconnected drum for cooperation in the actuation of said control means.

In testimony whereof I have hereunto subscribed my name, this 10 day of February 85 1927 at Zurich, Switzerland.

ARTHUR SCHORNO.
